UNITED STATES PATENT OFFICE.

JOHN M. IRMEN, OF ATLANTIC, IOWA.

WATCH-MAKERS' CALIPERS.

SPECIFICATION forming part of Letters Patent No. 439,156, dated October 28, 1890.

Application filed March 10, 1890. Serial No. 343,427. (No model.)

To all whom it may concern:

Be it known that I, JOHN M. IRMEN, a citizen of the United States, residing at the city of Atlantic, in the county of Cass and State of Iowa, have invented a new and useful Caliper, of which the following is a specification.

My invention relates to improvements in that class of calipers which are used by watch-makers in properly adjusting balance-wheels and other wheels at true right angles to their axles; and the objects of my improvements are to facilitate the adjustment of wheels on their axles, so that they will project therefrom at true right angles to their axles; also, to facilitate the adjustment of the periphery of wheels, so that all parts thereof will be equidistant from the axle; also, to facilitate the poising of wheels to determine if they balance on their axles. I attain these objects by the device illustrated in the accompanying drawings, in which—

Figure 1 is a perspective view of the calipers, showing a wheel secured within its jaws. Fig. 2 is a perspective view of a portion of the device, showing one of the jaws and parts contiguous thereto. Fig. 3 is a perspective view of the pivot of the caliper-sections. Fig. 4 is a longitudinal vertical sectional view, taken on the broken line $x-x$, Fig. 2, of one of the jaws and parts contiguous thereto.

Similar letters refer to similar parts throughout the several views.

The bent levers or sections C and D are pivotally connected by means of the pivot d' , which passes snugly through the section C and loosely through the section D, and projects at each end beyond the sections. It is provided with the ledge e' , which rests on the upper side of the section D.

A is an arm pivoted to the upper side of the section C. It is composed of the section e' and the bent section a^2 , pivotally connected by the rivet i . The bent section a^2 is provided with the projecting pin a' , which serves as a handle for the arm A.

The face of each caliper-jaw is provided with several circular cavities g , of different diameters, which taper as they extend inward, as shown in Fig. 4. Those ends of the caliper levers or sections C and D which have the jaws are provided with V-shaped notches d .

They also have grooves a cut on the upper and under surface of each near the face of the jaws, which form next to the face of the jaws sharp edges e . In those ends of the caliper-sections C and D which are not provided with the jaws are the circular cavities b .

E is an ordinary watch balance-wheel secured within the caliper-jaws by having each end of its axle inserted in a cavity g .

My device is operated as follows: A wheel is placed between the jaws of the calipers, with each end of its axle inserted in a suitable cavity g . The arm A is then adjusted so that the inner end of its bent section a^2 will come in contact with the side of the wheel at a point near its periphery, as shown in Fig. 1. The wheel is then revolved with the finger, and if the wheel projects from its axle at a true right angle to its axle the section a^2 will remain at all times during the revolution of the wheel in contact with it; but if it is not at a true right angle the section a^2 of the arm at some time during the revolution of the wheel will not be in contact with the wheel, and thus it can readily be determined in what direction the wheel should be bent or sprung in order to have it project at a true right angle from its axle, and if it is found not to project at a true right angle the ends of the axle are then removed from the cavities g and the axle inserted in the notches d and pressed firmly into the same. The jaws are then closed firmly against the wheel, and it is bent or sprung with the fingers in the proper direction to cause it to project at a true right angle from its axle.

To determine if all parts of the periphery of a wheel is equidistant from its axle, insert each end of the axle in a cavity g , as before explained, and adjust the arm A so that the inner end of the section a^2 will come in contact with the periphery of the wheel. Then by revolving the wheel it can readily be determined by the position of the section a^2 of the arm what portion, if any, of the periphery should be removed to make all parts thereof equidistant from the axle. To determine if a wheel balances on its axle, the calipers are held by the hand in a horizontal position, and the axle of the wheel is placed across the edges e in such a position that the wheel is suspended by its axle between the

100

jaws without coming in contact with them. Then if the wheel does not balance on its axle the heaviest portion will gravitate downward and cause the wheel to turn.

5 When the calipers are laid down on a table or bench, with a wheel secured within its jaws by means of having the ends of the axle inserted in the cavities *g*, the wheel is prevented from coming in contact with the table or bench 10 and thus bending its axle by means of the projected ends of the pivot *d'*, which serve as supports for that portion of the calipers having the jaws.

Having described my invention, what I claim 15 as new, and desire to secure by Letters Patent, is—

1. In watch-makers' truing-calipers, the combination of the bent levers or sections *C* and *D*, pivotally connected together, and each 20 lever being provided with a notched jaw, substantially as described.

2. The combination, in watch-makers' truing-calipers, of the bent levers or sections *C* and *D*, pivotally connected together, and each 25 lever being provided with a jaw having a *V*-shaped notch, substantially as set forth.

3. The combination, in watch-makers' truing-calipers, of the bent levers or sections *C* and *D*, pivotally connected together, and each lever being provided with a jaw having a sharp edge formed next to its face for the purpose of poising thereon watch-wheels, substantially as set forth. 30

4. The combination, in watch-makers' truing-calipers, of the bent levers or sections *C* and *D*, pivotally connected together, and each lever being provided with a notched jaw having a sharp edge formed next to its face, substantially as set forth. 35

5. The bent lever or section *D*, provided at one of its ends with the notch *d*, the edge *e*, and cavity *g*, the bent lever or section *C*, pivotally connected by the pivot *d'* to the section *D*, and being provided at one of its ends with the notch *d*, the edge *e*, and cavity *g*, and the 40 jointed arm *A*, pivotally connected to the lever or section *C*, all combined substantially as described.

JOHN M. IRMEN.
